(57) **CLAIM**

We claim the ornamental design for a wrench set holder and display, as shown and described.

DESCRIPTION

FIG. 1 is a perspective view of a wrench set holder and display according to the invention.

FIG. 2 is a front side view of the wrench set holder and display shown in FIG. 1.

FIG. 3 is a back side view of the wrench set holder and display shown in FIG. 1.

FIG. 4 is a right side view of the wrench set holder and display shown in FIG. 1.

FIG. 5 is a left side view of the wrench set holder and display shown in FIG. 1.

FIG. 6 is a top side view of the wrench set holder and display shown in FIG. 1; and,

FIG. 7 is a bottom side view of the wrench set holder and display shown in FIG. 1.

The elements shown in broken lines are included for the purpose of illustrating environment and form no part of the claimed design. Any broken lines having unequal line segments illustrate the boundary of the claimed design.

1 Claim, 5 Drawing Sheets
